Primary Examiner — Ricky Pham(74) *Attorney, Agent, or Firm* — Burns & Levinson, LLP;
Joseph M. Maraia**CLAIM**

The ornamental design for a blender and blender base, as shown and described.

DESCRIPTION

FIG. 1 is a perspective view of a blender and blender base showing my new design;

FIG. 2 is a front view of the blender and blender base shown in FIG. 1;

FIG. 3 is a rear view of the blender and blender base shown in FIG. 1;

FIG. 4 is a side view of the blender and blender base shown in FIG. 1;

FIG. 5 is another side view of the blender and blender base shown in FIG. 1;

FIG. 6 is a top view of the blender and blender base shown in FIG. 1; and,

FIG. 7 is a bottom view of the blender and blender base shown in FIG. 1.

The broken lines in the drawings are for illustrative purposes only and form no part of the claimed design.
